CLAIM

The ornamental design for a mobile phone, as shown and described.

DESCRIPTION

1.1: Front view showing the mobile phone in an open configuration, with the capacitive stylus feature attached and the camera in a first position;

1.2: Back view thereof;

1.3: Left side view thereof;

1.4: Right side view thereof;

1.5: Top view thereof;

1.6: Bottom view thereof;

1.7: Front perspective view thereof;

1.8: Back perspective view thereof.

2.1: Front view showing the mobile phone in a closed configuration, with the capacitive stylus feature attached and the camera in a first position;

2.2: Back view thereof;

2.3: Left side view thereof;

2.4: Right side view thereof;

2.5: Top view thereof;

2.6: Bottom view thereof;

2.7: Front perspective view thereof;

2.8: Back perspective view thereof.

3.1: Front view showing the mobile phone in a closed configuration, with the capacitive stylus feature attached and the camera in a second position;

3.2: Back view thereof;

3.3: Left side view thereof;

(Continued)

- 3.4: Right side view thereof;
 3.5: Top view thereof;
 3.6: Bottom view thereof;
 3.7: Front perspective view thereof;
 3.8: Back perspective view thereof.
 4.1: Front view showing the mobile phone in an open configuration, with the capacitive stylus feature detached and the camera in a second position;
 4.2: Back view thereof;
 4.3: Left side view thereof;
 4.4: Right side view thereof;
 4.5: Top view thereof;
 4.6: Bottom view thereof.
 5: Back perspective view showing the mobile phone in an open configuration, with the capacitive stylus feature detached and shown side-by-side with the rest of the mobile phone design, and the camera in a first position.
 6.1: Front view showing the mobile phone in an open configuration, with the capacitive stylus feature detached and the camera in a first position;
 6.2: Back view thereof;
 6.3: Left side view thereof;
 6.4: Right side view thereof;
 6.5: Top view thereof;
 6.6: Bottom view thereof;
 6.7: Front perspective view thereof;
 6.8: Back perspective view thereof.
 7.1: Front view showing the mobile phone in a closed configuration, with the capacitive stylus feature detached and the camera in a first position;
 7.2: Back view thereof;
 7.3: Left side view thereof;
 7.4: Right side view thereof;
 7.5: Top view thereof;
 7.6: Bottom view thereof;
 7.7: Front perspective view thereof;
 7.8: Back perspective view thereof.
 8.1: Front view showing the mobile phone in a closed configuration, with the capacitive stylus feature detached and the camera in a second position;
 8.2: Back view thereof;
 8.3: Left side view thereof;
 8.4: Right side view thereof;
 8.5: Top view thereof;

- 8.6: Bottom view thereof;
 8.7: Front perspective view thereof;
 8.8: Back perspective view thereof.
